UNITED STATES PATENT OFFICE

2,493,125

DOOR-MOUNTED ELECTRIC SPACE HEATER

Nina L. Foster, Glendale, Calif., assignor to The
Calpat Corporation, Los Angeles, Calif., a cor-
poration of California

Application February 5, 1945, Serial No. 576,237

2 Claims. (Cl. 219—34)

1

My invention relates to an electric heater, and, since it finds particular utility in embodiments adapted for use as vertical wall heaters in bathrooms or other rooms of dwellings, such embodiments are hereinafter described, it being understood that my invention is not limited to such forms or uses.

The use of electric wall heaters, and particularly those of substantial vertical dimensions in rooms, such as bathrooms, is limited by the inconvenience or impossibility of installing such heaters in the walls either during or after the completion of construction of the dwelling because of lack of sufficient wall space, the necessity of cutting tile and studs or rearranging pipes and the necessity of providing proper insulation. It is an object of my invention to avoid these difficulties and to facilitate the installation of an electric heater by combining the electric heater with a door.

In many rooms, if an electric heater carried by the door is energized when the door is open, there is great danger of damage by excessive heat or fire to the walls, fixtures, or furnishings of the room. It is another object of my invention to provide an electric door heater having circuit control means so designed that the heater may be energized only when the door is in closed or substantially closed position. It is desirable that the circuit control means be of such character that it cannot be contacted by the human body in a manner to cause injury, and it is a corresponding object of my invention to provide an electric door heater having circuit means and circuit control means such that the electric circuit cannot be accidentally closed between them by a human body or human hand.

It is another object of my invention to provide an electric door heater having manual control means, so that the electric heater may be readily energized and deenergized when the automatic circuit control means is closed.

Other objects and advantages of my invention are described in the following specification, which will be more readily understood by reference to the accompanying drawing, in which

Fig. 1 is a front view of a door bearing an electric heater in accordance with my invention;

Fig. 2 is an enlarged fragmentary sectional view taken as indicated by the line 2—2 of Fig. 1;

Fig. 3 is a view of that side of the door opposite the side illustrated in Fig. 1;

Fig. 4 is a horizontal sectional view taken as indicated by the line 4—4 of Fig. 1; and

2

Fig. 5 is an enlarged fragmentary sectional view taken as indicated by the line 5—5 of Fig. 1.

Referring to the drawing, which is for illustrative purposes only, the numeral 11 indicates a door of conventional dimensions and including upper and lower stiles 12 and 13 and vertical rails 14 and 15 surrounding a central panel 16. The door 11 is connected by suitable hinges 17 to a door-frame 18, so that it may be swung between positions opening and closing the doorway or opening provided by the door-frame 18.

The panel 16 includes upper and lower frame members 19 and 20, respectively, which are suitably connected to the stiles 12 and 13, respectively, and side frame members 21 and 21a suitably connected to the rails 14 and 15, respectively. The frame members 19 to 21a, inclusive, may be formed of wood, metal, or suitable insulating material, such as asbestos sheeting, or the like.

20 Suitably connected, as by screws 22, to the rearward side of the stiles 12 and 13 and the rails 14 and 15 is an outer shell 23 which may be formed of wood or fibrous material but is preferably formed of metal. As is well illustrated in Figs. 2, 3, and 4, the outer shell 23 includes plane surfaced marginal portions 24 converging outwardly of the door 11 to intersection with a plane surfaced outer wall 25 parallel to the plane of the stiles 12 and 13 and the rails 14 and 15.

30 Suitably mounted within the outer shell 23 is an insulating shell 26 formed of any suitable material, such as asbestos. The insulating shell 26 includes upper and lower walls 27 and 28 converging rearwardly of the door 11 from the upper and lower frame members 19 and 20, respectively, to intersection with an outer wall 29 of the insulating shell 26. The outer wall 29 is parallel to and adjacent the outer wall 25 of the outer shell 23. The insulating shell 26 includes also vertical side

40 walls 30 and 31 extending from the side frame members 21 and 21a to intersection with the outer wall 29. Suitably secured to and covering the inner surface of the insulating shell 26 is an inner shell 32, preferably made of metal and with its 45 inner surface polished to provide a reflecting surface.

Mounted within the inner shell 32 is a plurality of electrical resistors or heater means or elements, illustrated in the drawing as two in number and indicated by the numerals 33 and 34. The heater elements 33 and 34 may be of any desired construction and supported in any suitable manner. As illustrated in the drawing, each of the heater elements 33 and 34 is in the form of a 55 coil of copper wire 35 surrounding a core 36 of in-

sulating material, the core 36 being supported at each end by brackets 37 mounted on the inner surface of the inner shell 32.

Secured to the inner surface of the frame members 19 to 21a, inclusive, is a guard in the form of a grill 38, preferably formed of metal and with openings therein of such dimensions as to prevent bodily contact with the heater elements 33 and 34 while permitting the passage of warm air therethrough. Disposed within the upper stile 12 and the rail 15 is a primary circuit means 39 which includes two conductors 40 and 41 electrically connecting the heater elements 33 and 34 through a manual control switch 42 to two movable contacts 43 and 44.

As is best illustrated in Fig. 5, the movable contacts 43 and 44 are mounted in a contact box 45 secured in a recess in the edge of the rail 15, so that the outer surface of the contact box 45 is flush with the edge of the rail 15. Each of the movable contacts 43 and 44 includes a projecting portion 46 curved so that, as the door 11 is swung to closed position, the projecting portions 46 extend into an opening 47 in a second contact box 48 mounted in the door-frame 18 with its outer surface flush with the inner surface of such frame. Mounted in the second contact box 48 are two stationary contacts 49 adapted for engagement by the projecting portions 46 of the movable contacts 43 and 44 when the door 11 is swung to closed position. The stationary contacts 49 are connected by conductors 50 disposed within the door-frame 18 and the wall adjacent to a source of electrical current.

As is well illustrated in the drawing, the movable contacts 43 and 44 and the stationary contacts 49, which constitute an automatic circuit control means, are positioned at such an elevation as to be out of reach of children, and the stationary contacts 49 are so disposed within the second contact box 48 as to prevent the circuit from being closed between them by a human body or human fingers, thus making impossible accidental bodily injury.

Inasmuch as the doorways and doors to bathrooms and dwelling rooms are of substantially standard dimensions, it is contemplated that the manufacture of doors of the character hereinbefore described in very few different dimensions will satisfy the demand for installations in all types of rooms.

Since it is necessary in order to install the door heater of my invention only to install the second contact box 48 and the conductors 50 in the door-frame 18, it will be seen that such installation does not require the cutting of the tile or other wall surface or the rearrangement of any piping within the wall or the utilization of any area of the wall surface. Inasmuch as, even though the manual switch 42 be in position closing the circuit between the heater elements 33 and 34 and the source of current, such circuit is not closed until the door 11 is in closed or substantially closed position, the heater elements 33 and 34 will never be energized when the door 11 is opened or partially opened, and hence the danger of damage from heat or fire to fixtures, walls, or furnishings adjacent the door in its opened or partially opened position is eliminated.

While I have illustrated and described an embodiment of my invention in which the door is movable by virtue of a hinged connection with the

door-frame and in which the electrical heater is vertically elongated, it will be understood that my invention is capable of use in connection with doors having different mountings and supporting heaters of different forms. Various other modifications and additions which also embody my inventive concept will occur to those skilled in the art, and my invention is therefore to be understood as not restricted to the specific embodiment hereinbefore, described but as including all of the variations which come within the scope of the claims which follow.

I claim as my invention:

1. A space heating unit, comprising: a door frame having an entrance-way opening; a door pivoted within said door frame and operative to open and close said opening; a space heater mounted on said door and including an electrical heating element; an electrical circuit for said heating element; a first electrical leaf spring element on the door frame and connected in the circuit; and a second electrical leaf spring element carried by the door and electrically connected to the heating element, said second leaf spring element being adapted to yieldingly engage said first leaf spring element to close the electrical circuit to the heating element to energize the same when the door is pivoted to closed position and to disengage said first leaf spring element when the door is pivoted to open position so as to de-energize the heating element.

2. A space heating unit, comprising: a door frame having an entrance-way opening; a door pivoted within said door frame and operative to open and close said opening; a space heater mounted on said door and including an electrical heating element; an electrical circuit for said heating element; a first contact box carried by the door frame and provided with an opening; a first flexible electrical contact element disposed within said first contact box; a second contact box disposed in an edge of the door; and a second flexible electrical contact element disposed within said second contact box and having a curved end projecting from said second contact box and concentric with the pivotal axis of the door, said second contact element being adapted to enter said opening and to yieldingly engage said first contact element to close the electrical circuit to the heating element to energize the same when the door is pivoted to closed position and to move out of said opening to disengage said first contact element when the door is pivoted to open position so as to de-energize the heating element.
